UNITED STATES PATENT OFFICE.

CHARLES A. HULTQUIST, OF LOWELL, ARIZONA TERRITORY.

VALVE.

964,970.

specification of Letters Patent. Patented July 19, 1910.

Application filed November 22, 1909. Serial No. 529,242.

To all whom it may concern:

Be it known that I, CHARLES A. HULTQUIST, a citizen of the United States, residing at Lowell, in the county of Cochise and Territory of Arizona, have invented new and useful Improvements in Valves, of which the following is a specification.

My invention relates to an improved valve motion, which is especially designed for the operation of hammers, rock-drills, &c., driven by an elastic fluid under pressure.

It consists in a means for holding the valve in position after it has been moved or tripped by the action of air in the cylinder.

It also comprises details of construction which will be more fully explained by reference to the accompanying drawings, in which—

Figure 1 is a sectional elevation of the cylinder and valve chamber. Fig. 2 is a modification of the device.

A is the cylinder in which the piston B is adapted to reciprocate. This piston may act as a hammer to operate a rock-drill, or a riveting hammer, or for other equivalent purposes where reciprocating motion is required.

C is the valve chamber, in which the valve is adapted to reciprocate. The valve consists of a stem D, and the pistons 1—2—3, which fit and reciprocate within the valve chamber C.

4 are the heads of the valve chamber, and either of these may be removed, and the valve removed; the pistons 1—2—3 being of uniform diameter so that the valve may be moved from either end of the valve chest by removing either of the plugs 4.

The ends or smaller diameters 5 and 6 of the valve are adapted to reciprocate in chambers 7 in which these ends fit.

8 is the inlet passage for the fluid under pressure, and the head 1 moves so as to open communication with either one side or the other of this head, and between it, and either of the heads 2 or 3. 9 and 9^a are ports connecting this intermediate space with opposite ends of the cylinder A; and 10—10^a are ports connecting the central portion of the valve chest with the chambers 7 in the heads 4.

In Fig. 2 I have shown stems 5^a and 6^a projecting inwardly from the heads 4 of the valve chest, and the chambers 7^a are formed in the ends of the valve heads 2 and 3 so that instead of these small plungers being op-

erated with the valve, the valve moves with relation to the fixed plungers, the operation however is essentially the same in both cases.

11—11^a are ports opening from the cylinder into the valve chest exterior to the heads 2 and 3, and 12—12^a are the ports opening through the side of the valve chest, and which are exposed by the movements of the heads 2 and 3 so as to alternately exhaust the actuating fluid from the ends of the cylinder.

The operation of the device will then be as follows: The valve having the position shown in Fig. 1, the head 3 has been moved to the right so as to open communication between the inlet port 8 and the port 9^a which leads to the right end of the cylinder A, while the head 1 will be in position to cut off the impelling fluid from the ports 9 and 10. The port 10^a being opened simultaneously with the port 9^a, the impelling fluid will pass through this port into the chamber 7 at the right, and behind the plunger 6, at the same time while the fluid is entering the right end of the cylinder A, the pressure in both being the same. The pressure within the cylinder will force the piston B toward the left end of the cylinder, and as the port 9 is in open communication with the port 12, the fluid at the left end of the cylinder will be exhausted through these ports, and when the piston has moved far enough to uncover the port 11, the fluid which has impelled it to the left, will pass through this port and behind the head 2 of the valve. The area of this head being so much larger than the area of the plunger 6, the pressure will overcome that in the right hand chamber 7, and the valve will be immediately forced to the right end of its stroke; thus causing the head 2 to cover and inclose the exhaust port 12, the head 3 to uncover the exhaust port 12^a, and the head 1 to be moved to the right so as to open communication between the inlet port 8, the port 9, and the port 10, which supplies the left chamber 7 behind the plunger 5. In this manner the valve is perfectly balanced and cushioned, and the alternate changing of pressure at opposite ends will automatically operate it in unison with the movements of the piston within the main cylinder.

The action of the plungers 5 and 6 to hold and steady the valve may be explained as follows: The piston or hammer B will always travel past the ports 11 and 11^a in its reciprocations, as the valve requires a

the time to trip or change its position, and
er it has changed, the piston will still con-
ue its movement in the same direction un-
the opposing fluid pressure has cushioned
and the return stroke is commenced.

In the position shown, the pressure behind
head 3 has been exhausted together with
exhaust from the left end of the cylinder,
ore the piston B has returned far enough
over the port 11*, therefore there would
nothing to hold the valve in its place if
ere not for the pressure behind the plun-
6.

Having thus described my invention, what
aim and desire to secure by Letters Pat-
is—

The combination with the cylinder, of a
procating engine, having inlet ports con-
ting with opposite ends and secondary
ts connecting with the central portion
he cylinder, of a valve chamber, with the
tral portion of which the cylinder inlet
ts communicate, and with the outer ends
which the secondary ports communicate,

said valve chamber having end-heads and 25
having a centrally disposed supply port and
exhaust ports between said central port and
the cylinder ends, a valve consisting of a
stem with heads between which the main
ports are exposed, a central head adapted to 30
open the supply port to either side by the
reciprocations of the valve, said reciprocations
alternately closing the exhaust ports
of the valve chambers, plunger extensions
of less diameter than the said heads, the end 35
heads of the cylinder having chambers within
in which the said extensions are movable and
guided, and ports through which pressure is
admitted behind said extensions, simultane-
ously with the admission to the correspond- 40
ing cylinder end.

In testimony whereof I have hereunto set
my hand in the presence of two subscribing
witnesses.

CHARLES A. HULTQUIST.
